(57) **CLAIM**

The ornamental design for a suit backpack, as shown and described.

DESCRIPTION

FIG. 1 is a top front left side perspective view of a suit backpack shown in a closed configuration;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is a top, rear, left side perspective view of the suit backpack shown in an open configuration;

FIG. 9 is a front elevation view thereof, shown at a reduced scale;

FIG. 10 is a rear elevation view thereof, shown at a reduced scale;

FIG. 11 is a left side elevation view thereof;

FIG. 12 is a right side elevation view thereof;

FIG. 13 is a top plan view thereof, shown at a reduced scale; and,

FIG. 14 is a bottom plan view thereof, shown at a reduced scale.

The broken lines in the figures illustrate the portions of the design that form no part of the claimed design.

1 Claim, 13 Drawing Sheets
